DESIGN FOR A KEY RING OR SIMILAR ARTICLE

Lawrence E. Baer, Attleboro, Mass., assignor to
The Baer & Wilde Company, Attleboro,
Mass.

Application June 20, 1933. Serial No. 48,475

Term of patent 14 years

To all whom it may concern:

Be it known that I, LAWRENCE E. BAER, a citizen of the United States, residing at Attleboro, in the county of Bristol and State of Massachusetts, have invented a new, original, and ornamental Design for a Key Ring or Similar Article, of which the following is a specification, reference being had to the accompanying drawing, forming part thereof.

Figure 1 is an obverse view of a key ring, showing my new design.

Figure 2 is a reverse view of the same.

The essential feature of the invention resides in a pair of divergent bars, the outer ends of which are of circular form and are connected

to a pair of rings, the bars at their upper ends being connected to simulate a hook and eye, the connection being surmounted by a second eye, combined with a chain the ends of which have short bars connected thereto which latter are engaged through the respective rings, the bars of the chain being of a length in excess of that of the diameter of the rings.

I claim:

The ornamental design for a key ring or similar article as shown and described.

In testimony whereof I have signed my name to this specification in the presence of two subscribing witnesses.

LAWRENCE E. BAER.
